HUMIDIFIER

William G. Macy, Bloomington, Ill., assignor to
 American Foundry & Furnace Company,
 Bloomington, Ill., a corporation of Illinois

Application November 14, 1938, Serial No. 240,287

2 Claims. (Cl. 126—113)

This invention relates to humidifiers of the type usually associated with warm air heating furnaces and which are provided for the purpose of maintaining proper air humidity in the heated building.

Open tank humidifiers in furnaces of this type are very old in the art and have been used with indifferent success for many years. Such devices fail of attaining satisfactory results by reason of one or more of the following faults: the surface area of the water being too small to be effective; water impurities forming scum on the water surface, preventing rapid evaporation; surface area of the water located improperly in relation to the air currents; and evaporator tank improperly located to heat properly.

It will be appreciated that these factors are sharply variable under the widely different conditions met with in heating practice and, therefore, the problem which appears to be relatively simple on the surface is really quite involved and complicated when it is desired to control humidity within a reasonable range.

Various types of spray humidifiers have been developed, but many faults inherent in this type of apparatus, such as clogging of nozzles, variations in water pressure, etc., make this type less desirable than the simpler evaporator tank type when a proper structure and effective control means is available.

The particular object of this invention is to provide a simple evaporator tank type humidifier that may be controlled to maintain desired humidity conditions.

Another object is to provide a small evaporator tank humidified of widely variable evaporation capacity, easily controllable by conventional control apparatus.

And a still further object is to provide a humidifier apparatus that may be located conveniently in the best position in the furnace and in firm heat conduction contact with the heater in order to attain the most effective results.

In the accompanying drawings I show a preferred embodiment of my invention, but it will be readily appreciated that the principles involved can be adapted to many variations in structure.

Now referring to the drawings:

Fig. 1 is a cross sectional side elevation view of a warm air furnace, showing my humidifier apparatus in position;

Fig. 2 is a broken perspective view of the humidifier apparatus as it appears looking angularly downward to better show the arrangement of the parts; and

Fig. 3 is an enlarged partially broken elevation view of the humidifier apparatus showing the wiring, piping and control system somewhat diagrammatically.

Now referring to Fig. 1, I show a general base member 10 on which is mounted a motor 11 driving a conventional blower 12 through a belt 13. This blower draws air downward through an air cleaner 23 and around horizontal heater tubes 16, then drives it vertically over the heater casing 14 and thence upward through a conventional duct distributing system (not shown).

As well illustrated, the combustion chamber 14 is heated by any conventional burner means 15, the one shown being for a gas burner. The heat from the hot gases is absorbed through the ribbed burner casing 14, the horizontal heater tubes 16 and the cast header 17 and then are conducted to the outside air through the stack 18.

The entire heater is encased in a conventional insulated sheet metal casing 19 which has various doors 20, 21 and 22 conveniently located for service, interior adjustments, etc.

As best shown in Figs. 2 and 3, it will be noted that I mount or set the evaporator pan 24 directly on top of the combustion chamber 14 with the contacting surfaces 14' and 24' in firm intimate conduction contact, which is assisted, of course, by the weight of the tank 24 with the weight of its water content. This materially assists in evaporation efficiency because the evaporator pan is located not only in position to best absorb heat from the heater casing, it being in one of the hottest locations, but also because it is an excellent position to be evaporated into the upwardly-moving, heat-expanded air stream. Even when the blower is not in operation, the evaporator pan thus located will continuously give off water vapors which will be of material assistance in maintaining proper humidity in the building.

However, this location is especially effected in my construction in which I trap or induct almost any desired fraction of the upwardly moving air stream in air tubes 28 which are cut angularly at the bottom to induct the air and to prevent resonance noises. This air is impinged downwardly on the surface of the water by elbows 29, and intimate agitated contact between the air and water is thus provided, and the surface of the water is continuously agitated in surface ripples. This action is not only effective because of this intimate impinged contact between the water and air but such action is further effective in preventing the formation of surface scum on

the surface of the water which would greatly reduce the evaporation capacity of the tank. It will also be appreciated that this action effects thorough aeration and thus stagnation is prevented. With this explanation it will be understood how I attain unusually effective results with a relatively small apparatus.

It will be further appreciated that my tube and elbow air duct structure enables me to readily adjust my apparatus for variable results by selecting the proper number of tubes for my apparatus. Also it gives me a standardized unit structure which is adaptable to a variety of furnace sizes and heating conditions.

The evaporator tank 24 is supplied with water through a connector pipe 26 from a conventional supply tank 25 equipped with a float valve 27. This arrangement is so common and well understood that it will not be described in detail.

Now referring to Fig. 3, the float tank 25 is served by a service water pipe line 30 in which is inserted a solenoid controlled water valve 31 controlled by a conventional humidistat 32. It will be understood, of course, that this humidistat is located at any desirable location in the building and that when humidity rises above the desired level, it actuates the solenoid valve 31, closing the water line 30, thus shutting off water to the evaporator tank until the humidity drops to the lower desired level when the valve 31 is again actuated and the water line opened. This operation is conventional and is believed to be well understood. The operation is effected electrically from an electric circuit 35. Inasmuch as this arrangement is conventional, no further explanation is deemed necessary.

Again referring to Fig. 3, the burner 15, in this case a gas burner, is served by a gas pipe line 36 in which a solenoid control valve 33 is inserted. This valve is controlled by a conventional thermostat 34 located at any convenient location and actuates the control of the electric circuit for opening or closing the valve 36 in response to variations in temperature outside of the desired range. This circuit also controls the operation of the motor 11 which drives the fan 12.

From the foregoing description, it will be ap-

parent that I have provided a simple evaporator tank type humidifier of widely variable capacity that is easily and effectively controllable by conventional control apparatus and which is of such structure that it may be conveniently and economically installed in warm air heating furnaces of various designs and capacities.

I claim:

1. In a humidifier for warm air furnaces with air circulating fan, an evaporator tank adapted to be supported in intimate contact on top of the combustion chamber, water supply means within said tank, means to control said supply means responsive to humidity conditions, multiple vertical air ducts adjacent the combustion chamber to induce upwardly moving warm air currents from within the furnace and impinge same downward on the surface of the water in the evaporator tank to cause agitation and prevent formation of scum, and thermostatic control means to control fan operation responsive to temperature conditions whereby humidity is supplied slowly by natural evaporation from the evaporator tank when the circulating fan is not in operation and rapidly when the fan is operating.

2. In a humidifier for warm air furnaces having a convertible combustion chamber and horizontal heater tubes extending from said chamber; an evaporator tank adapted to be supported in intimate contact on top of the combustion chamber, water supply means within said tank, means to control said supply means responsive to humidity conditions, multiple vertical air ducts between the header tubes and adjacent the combustion chamber, said ducts being positioned to trap upwardly moving air currents from within the furnace, heat the air so trapped and impinge same downward on the surface of the water in the evaporator tank to cause agitation and prevent formation of scum, and thermostatic control means to control fan operation responsive to temperature conditions whereby humidity is supplied slowly by natural evaporation from the evaporator tank when the circulating fan is not in operation and rapidly when the fan is operating.

WILLIAM G. MACY.
